VLADIMIR YOURKEVITCH, OF PARIS, FRANCE

TRACE OF SHIPS' LINES

Application filed October 3, 1929, Serial No. 397,007, and in Germany May 7, 1928.

The invention relates to certain improvements in the trace of ships' lines. Its object is to provide a hull whose resistance to forward motion is reduced for a given displacement, whereby a saving in the power necessary to propel the ship is effected, assuming that the displacement, the length and the speed remain the same.

As is known, the resistance to forward motion in ships is made up of two factors.

1. A general frictional resistance.
2. A direct resistance to forward motion termed hereinafter residuary resistance.

The general frictional resistance is due to the rubbing of the water against the ship's hull; this resistance is proportional to the immersed surface of the hull, to its cleanliness, its general condition and the like; it is scarcely possible to find means for substantially reducing this resistance.

On the other hand, the residuary resistance may be decreased. This resistance is produced in great part by the wake which depends on the form of the hull. Ships of the same length and displacement may have residuary resistances differing in the ratio of 1 to 2.

The object of the present invention is to provide a trace for ships' lines enabling the residuary resistance to be considerably reduced.

Other advantages and peculiarities of the invention will become apparent from the description which is about to be made thereof in conjunction with the accompanying drawings in which:

Fig. 1 illustrates the traces of several of the transverse frames or ribs of the ship according to usual design and according to the design of the present invention.

Fig. 2 illustrates the curves of the surface areas of the various frames at different points along the length of the ship according to usual design and according to design in conformance with the invention. A ship's hull and the profile of the wave which is formed in the case of the usual design and in the case of the design according to the invention, has likewise been illustrated diagrammatically in this figure.

Fig. 3 is a half-breadth plan of the hull of a ship at the water line according to the usual design and to the present invention.

Fig. 4 is a graph illustrating the resistance curves of different ships according to the usual design and to the present invention.

In the different figures of the drawings, the fine line refers to the usual design and the thick continuous or dotted line refers to the design according to the present invention.

As is apparent from the law of comparison which is applied to similar ships when their dimensions have the same linear ratio, the speeds vary as the square root of the linear dimension; speeds are generally compared by using the ratio

$$\frac{v}{\sqrt{L}} \quad 70$$

where L is the length of the ship.

From the tests which were carried out in the experimental tank, it has been found that the form and height of the wake which, as has been stated above, is the principal cause of the residuary resistance, are dependent to a great extent on the trace of the fore-part of the ship. When the coefficient

$$\frac{v}{\sqrt{L}} \quad 75$$

is comparatively low, equal to 1 for example, hardly any wave is formed at the stem, the stream lines can adapt themselves to the profile of the ship so that they produce neither waves nor eddies. On the other hand, when the speed increases, the fore-part of the ship so to speak pushes the water before it so that the latter has not time to adapt itself to the profile of the ship and the wake is produced.

The thrust of the wake has a centre of pressure on either side of the ship which is displaced more and more towards amidships as the speed increases. It gradually reaches amidships for a value of

$$\frac{v}{\sqrt{L}} = 3. \quad 95 \quad 100$$

This resistance is the resistance to forward movement excluding the frictional resistance.

In Fig. 3 which illustrates diagrammatically the half-breadth plan at the water line of two ships built according to usual design and according to the present invention, the different positions of the centres of pressure have been indicated for the corresponding values of

$$10 \quad \frac{v}{\sqrt{L}}$$

which have been plotted as abscissæ. As has been indicated above, when

$$15 \quad \frac{v}{\sqrt{L}} = 1,$$

the centre of pressure is right forward and for

$$20 \quad \frac{v}{\sqrt{L}} = 3,$$

the centre of pressure is amidships. It may be taken for granted that the displacement of the centre of pressure is roughly proportional to the speed and by uniformly dividing up the space from 1 to 3, the different positions of the centre of pressure for the corresponding values of

$$30 \quad \frac{v}{\sqrt{L}}$$

may be obtained. The distance, in meters, of the center of pressure from the bows of the ship is therefore given by the formula

$$35 \quad X = \left(\frac{v}{\sqrt{L}} - 1 \right) \frac{L}{4}$$

where L is the length of the ship.

Assuming that it is desired to build a ship having a definite displacement, length and speed, the position of the centre of pressure for a given ship can be immediately read off the diagram of Fig. 3.

The method of tracing in conformance with the invention consists in making the hull of the ship as narrow as possible in the neighbourhood of the centre of pressure, the internal arrangements being of course allowed for. In this manner, since at this point the hull makes a very acute angle with the direction of motion, the residuary resistance will be considerably reduced. The diminution in the breadth of the hull in the neighbourhood of the centre of pressure is compensated by widening it in other places so as to maintain the displacement unchanged.

For example, if it be desired to build a liner 225 ms. long to steam at 25 knots, the ratio

$$\frac{v}{\sqrt{L}} = \frac{25}{\sqrt{225}} = \frac{25}{15} = 1\frac{2}{3}.$$

The diagram enables the centre of pressure which is at 37.5 ms. from the bows of the

ship to be located. The form of the ship is then traced and is made as narrow as possible at this point.

Thus the trace illustrated in heavy lines is obtained, the usual form of trace being illustrated by the thin line.

The ship's half-breadths at this point will be respectively a and b . For either case, the residuary resistances may be taken to be proportional to the squares of these lengths; the resistance ratio will therefore be

$$\frac{r_1^2}{r_2^2} = \left(\frac{a}{b} \right)^2.$$

As will be realized, a very substantial reduction in the residuary resistance is effected by tracing the hull in accordance with the design of the invention. This resistance may, in certain cases, be halved. As it has been assumed that ships having the same displacement, length and speed were being compared, the diminution of resistance thus obtained results in a corresponding decrease in the power necessary to drive the ship.

In the diagram of Fig. 4 the resistance curves of two ships, one according to current design, the other according to the present invention, have been plotted in terms of the speeds of the ships. These curves are obtained by taking the values in kilograms of the resistances as ordinates and the values of the ratio

$$\frac{v}{\sqrt{L}}$$

as abscissæ. It will be seen from this diagram that the skin friction r_1 is identical for the two types of boat and increases with the speed; on the other hand, the residuary resistances, r_1 in the case of the usual design and r_2 , for the one in conformance with the invention, very soon diverge; r_2 may be less than half r_1 .

In order to decrease the residuary resistance, not only may the trace of the hull be modified in the horizontal direction as has been indicated above, but also in the vertical direction.

In Fig. 1, the various transverse frames starting from the fore-part of the ship have been illustrated on the right, and the frames of the aft portion of the ship on the left. As has been stated above, the thin lines 1, 2, 3 . . . . illustrate the frames according to existing design, the heavy full lines A, B, C . . . . and chain dotted lines a , b , c . . . . illustrate two alternative forms of construction according to the present invention. The cross hatched portions bring out the difference in the trace of corresponding frames.

According to current designs and more especially at the fore-part of the ship, the frames are inclined outwardly at the level of the water line as can be seen in Fig. 1 in

the case of the frames 1 and 2 which are the nearest to the fore-part of the ship.

- As will be understood, during the forward motion of the ship, the frame 1 by its displacement exerts on the water not only various simple horizontal thrusts whose resultant is in the direction of the axis of the ship, but also, all along the upper immersed portion of the frame, a thrust perpendicular to the curvature of said frame, that is to say the frame 1 tends at each point of its length to thrust the water below the horizontal plane passing through such point, if, of course, the frame is inclined to the vertical at this point.
- It is this action which increases the height of the wake, which, as has been previously indicated, is due to the direct resistance to the forward motion of the ship.

By designing the different frames of the ship, and, in particular those situate near the fore-part thereof, in such manner that they shall always be practically vertical as far as the portion lying below the water line is concerned, as is the case for the frames A, B, C of the drawing, this particular resistance is further reduced to an appreciable extent.

By even making said frames distinctly concave as illustrated in Fig. 1 in the case of the frames *a*, *b*, *c*, the height of the wave is lowered to a very appreciable extent, the concavity so to speak choking the wave.

A ship's hull has been illustrated in longitudinal section in Fig. 2; in this figure as well as in Fig. 1, the heights of the wakes *x* and *y* which are produced in the two cases under consideration and which are the effect of the residuary resistance, have been illustrated. It will be seen that this height is very substantially reduced with the design in conformance with the invention; hence the like applies to the resistance which produced this wave.

The diagrams of Fig. 2 have been traced by plotting the linear distance of the various frames of the ship along the abscissa and the surface area of said frames along the ordinate axis. As may be realized in the case of speeds such as

$$\frac{v}{\sqrt{L}} = 1.6,$$

in a hull designed in conformance with the present invention the surface areas of the frames are much greater than usual amidships and very much smaller at the ends.

To sum up, with the present design, the concavity in the fore-part of the ship makes its presence felt both in the vertical and in the horizontal direction in each of the horizontal planes cutting the ship below the water line. This has moreover been expressed in the diagram of Fig. 2, in which, as has been pointed out, the areas of the vertical sections

perpendicular to the longitudinal axis of the ship have been plotted as ordinates.

As has been pointed out previously, by adopting the design indicated above, the residuary resistance which produces the wake is reduced to a marked extent, and, consequently, less power is required to drive a ship of given displacement and length at a given speed.

It is obvious that the invention has only been described above in conjunction with the accompanying drawings for a narrow speed range and merely in an explanatory but by no means limitative manner, and that it may include all alternatives in conformance with the spirit of the invention.

I claim:

1. A ship's hull having transverse frames reduced in breadth in the vicinity of the position of the center of pressure of the residuary resistance which varies with the ratio of the speed of the vessel to the square root of its length, the center of pressure being in the fore-part of the ship when the ratio is 1 and amidships when the ratio is approximately 3.

2. A ship's hull having transverse frames reduced in breadth in the vicinity of the position of the center of pressure of the residuary resistance which varies with the ratio of the speed of the vessel to the square root of its length, and other transverse frames which are increased in breadth to maintain the ship's displacement unchanged.
